UNITED STATES PATENT OFFICE

HERBERT L. BONE, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY BRAKING APPARATUS

Original application filed March 24, 1931, Serial No. 524,782. Divided and this application filed July 14, 1932. Serial No. 622,490.

My invention relates to railway braking apparatus, and particularly to braking apparatus of the type comprising braking bars located in the trackway adjacent a track rail 5 and arranged to be moved at times into engagement with the wheels of a car or vehicle.

The present application is a division of my copending application Serial No. 524,782, 10 filed March 24, 1931, for railway braking apparatus.

I will describe one form of braking apparatus embodying my invention, and will then point out the novel features thereof in claims.

15 In the accompanying drawing, Fig. 1 is a top plan view showing one rail of a railway track having associated therewith braking apparatus embodying my invention. Fig. 2 is a transverse sectional view of the braking 20 apparatus illustrated in Fig. 1, showing on a somewhat larger scale the positions which the parts occupy when the braking apparatus is engaging the car wheel. Fig. 3 is an enlarged detail view of a portion of the apparatus illustrated in Fig. 1. Fig. 4 is a sectional view taken on the line IV—IV of Fig. 3. Fig. 5 is a sectional view taken on the line V—V of Fig. 3.

Similar reference characters refer to similar parts in each of the several views.

Referring first to Fig. 1, the reference character 1 designates a railway track rail which is supported by tie plates 2 secured to the usual cross ties 3, and along which cars normally move in the direction indicated by the arrow. Located on opposite sides of rail 1 are two braking bars B and C, each comprising a plurality of beam sections 6. Each beam section 6 is provided with the usual 35 wheel engaging shoe 7. Pivotaly supported in the trackway adjacent each beam section 6 are a plurality of trunnions D. Each trunnion D is connected with the adjacent beam section by means of a resilient link G, the 40 links G being disposed at acute angles with the rail in such manner that movements of the beam sections in directions parallel to the track rail will result in movement of the sections toward and away from the rail, that 45 is to say, into the closed and open positions 50

of the braking apparatus. The construction of the links G is such, and the beam sections are supported in such manner, that when the braking bars are in their closed positions and a beam section is engaging a car wheel, thereby causing the springs of the links which are connected with such beam section to become compressed, a limited amount of tipping of this beam section will take place as illustrated in Fig. 2, this tipping causing the associated brake shoe to engage the car wheel at a higher point, and, therefore, a more effective point than would be the case if this tipping did not take place.

Pivotaly supported in the trackway are 65 two cranks 10 and 11. The crank 10 is provided with a pin 12, on which is journalled a driving link 13, the free end of which is provided with an upstanding post 14 which enters a suitable socket formed in the underside of the intermediate beam section 6 of braking bar B. It will be apparent, therefore, that clockwise movement of crank 10 will move the intermediate section 6 of braking bar B toward the left as viewed in Fig. 1. 70 In similar manner, crank 11 is connected with the intermediate section 6 of braking bar C by means of a driving link 21 so that this intermediate section will move toward the left, as viewed in Fig. 1, when crank 11 75 rotates in a counter-clockwise direction. The free arms of the cranks 10 and 11 are intended to be connected by means of links 15, with suitable operating mechanism for 80 rotating the cranks simultaneously in opposite directions, such for example, as the operating mechanism shown and described in my United States Letters Patent No. 1,812,191, granted on June 30, 1931, for railway 85 braking apparatus. This operating mechanism is omitted from the drawing since it forms no part of my present invention.

The beam sections of each braking bar are connected together at their adjoining ends by suitable articulated connections embodying my invention, in such manner that movements, in directions parallel to the rail 1, of the intermediate section 6 which are operated by the cranks 10 and 11, will cause corresponding movements of all of the sections 90 95 100

of the associated braking bar. One form of articulated connection which may be employed for this purpose is shown in detail in Figs. 3, 4 and 5. As here shown, each 5 beam section is provided at one end, preferably the entering end, with an integral web 16 having an integral upstanding circular pin or post 16^a which enters a bushed circular recess or socket 17^a located in the under- 10 side of a projecting portion 17 formed on the adjoining end of the adjacent beam section. To relieve the lateral strain on the post 16^a due to the previously described tipping of the beam sections when the beam sections are 15 engaging a car wheel, the web of each section is also provided with a laterally projecting abutment 19 which engages a corresponding abutment 20 formed on the adjoining end of the adjacent beam section.

20. With the apparatus constructed in this manner, it will be apparent that if crank 10 is rotated in a clockwise direction and crank 11 in a counter-clockwise direction, as described hereinbefore, the braking bars B 25 and C will each move toward the left as a unit, but that, if crank 10 is rotated in a counter-clockwise direction and crank 11 in a clockwise direction, the braking bars B and C will then each be moved toward the right 30 as a unit. Furthermore, it will also be apparent that when the braking bars are in their closed positions, and a car wheel is about to pass from a given beam section to the beam section next in advance, the entering 35 end of the beam section next in advance will not only be forced away from the rail the same distance as the leaving end of the given section, but will also be tipped or raised approximately the same amount as 40 the given beam section is raised by engagement with the car wheel. As a result, when the car wheels pass from one beam section to the next, there is no shock either to the car wheels or to the braking apparatus so that a 45 more effective braking action takes place, and the life of the apparatus is greatly lengthened due to decreased strain.

One advantage of braking apparatus embodying my invention is that the beam sections, 50 in addition to performing their normal function which is to operate the brake shoes, also form part of the operating mechanism of the apparatus. This makes the use of driving bars and complicated driving 55 mechanism unnecessary and permits a greater access to the crank structures and associated parts. Furthermore, by reducing the number of operating parts to a minimum, it reduces the amount of friction in the braking 60 apparatus, thereby permitting a reduction in the amount of power which must be provided to operate the apparatus. In addition, the number of parts subject to wear is reduced, and the cost of manufacture is also reduced. 65. Although I have herein shown and de-

scribed only one form of railway braking apparatus, it is understood that various changes and modifications may be made therein within the scope of the appended claims without departing from the spirit and scope of my 70 invention.

Having thus described my invention, what I claim is:

1. As a new article of manufacture, a beam section for a car retarder braking bar, said beam section being provided at one end with a vertically extending post and at the other end with a projection formed with a socket adapted to receive a post formed on the end 80 of a similar beam section.

2. As a new article of manufacture, a beam section for a car retarder, said beam section being provided at one end with a web having an integral upstanding post and at the other end with an overhanging projection formed with a socket adapted to receive a post on the end of a similar beam section. 85.

3. Railway braking apparatus comprising two beam sections located end to end beside a track rail, a web integral with one end of one section, a vertically disposed post integral with said web, a projecting portion integral with the abutting end of the other section, said projecting portion being provided with a socket adapted to receive said post, means connected with one and only one of said sections for moving such section in directions parallel to the track rail, said post and socket serving to connect the sections together in such manner that movement of such single section causes corresponding movements of both sections, and means effective when said sections are moved in directions parallel to said track rail for moving said sections toward the track rail. 100.

In testimony whereof I affix my signature.
